ADJUSTABLE STROKE METERING PUMP

Martin Madsen, Alhambra, and Albert H. Ziegler, Hollywood, Calif., assignors to Madsen Iron Works, Huntington Park, Calif., a corporation of California

Application July 18, 1938, Serial No. 219,874

2 Claims. (Cl. 74—40)

Our invention relates to means for delivering a measured quantity of fluid continuously over an extended period of time, and the invention relates in particular to a metering pump adjustable during its operation to vary the volumetric delivery or measured flow of the liquid delivered.

Although our present invention may be used to deliver a continuous measured flow of various fluids, it is of especial utility in road making machines of the character disclosed in the application of Martin Madsen, Serial No. 123,183, filed January 30, 1937, this road making machine including a vehicle adapted to be moved continuously along the road and having a mixer to continuously receive aggregate road surfacing material and to discharge such material thoroughly mixed with a binder and in condition to be spread out so as to form a road surfacing layer. In a road making device of this character, best results are obtained only when the proper proportion of binder material is mixed with the aggregate materials which are placed in ridges or windrows along the path travelled by the road making machine. To accomplish this proportionate delivery of the binder, which is ordinarily an asphalt road oil, to the aggregate materials, a displacement pump is connected so that its speed of operation will vary in accordance with the speed of forward travel of the road making machine, and consequently so that a given quantity of binder will be fed to the aggregate materials during each and every unit distance of forward travel of the road making machine.

It is an object of the present invention to provide a simple and durable variable volume pump adapted so as to be continuously operated to deliver a flow of fluid at a rate determined in accordance with the setting of the adjustable parts of the pump.

It is a further object of the invention to provide a metering pump of the character above described, having a drive operable at constant speed, and means for the variable transmission of motion from this drive member to a pump piston.

It is a further object of the invention to provide a metering pump, the volumetric delivery of which may be varied during the operation thereof.

A further object of the invention is to provide in a measured flow fluid delivery device a pumping chamber having a movable wall, a rocker arm connected to this wall, and pivot means adapted to be moved along the rocker arm so as to vary

the distance of the fulcrum point of the rocker arm relative to its ends, and means for transmitting a reciprocating motion to the outer end of the rocker arm.

Further objects and advantages of the invention will be brought out in the following part of the specification.

Referring to the drawings which are for illustrative purposes only:

Fig. 1 is a plan view of a preferred embodiment of our invention.

Fig. 2 is a partly sectioned side elevation of the device shown in Fig. 1.

Fig. 3 is a partly sectioned face view looking toward the right end of the device shown in Fig. 2.

Fig. 4 is a fragmentary section taken on a plane represented by the line 4—4 of Fig. 2.

Fig. 5 is a fragmentary section taken as indicated by the line 5—5 of Fig. 3.

As shown in Figs. 1 and 2, the metering pump includes a pump member 10 comprising a casing having formed therein in side-by-side relation a pair of double acting pump units including piston rods 11, each of which, as shown in Fig. 2, is connected to a movable fluid displacing wall in the form of a piston 12 which slides in a cylinder 13 so as to move fluid through ports 15 leading into a valve manifold structure 16 having intake and discharge valves which are not shown in detail owing to the fact that they correspond to general practice. By means of screws 18 a support 19 is secured to the rod end of the pump member 10, this support 19 having a vertical wall 20 at the left end thereof, a box-like central portion 21, and a cross-head guide section 22 formed so as to provide cross-head guides 23 and 23a lying in side-by-side relation.

As best shown in Figs. 3 and 5, the cross-head guides 23 and 23a have substantially cylindrical bores 24 axially aligned with the piston rods 11. Cross-heads 25 and 25a are threaded on the outer ends of the piston rods 11, as shown at 26, these cross-heads each comprising a cylindrical body having a shallow annular channel 27 intermediate its end, a vertically disposed opening or chamber 28, and a lateral bore 29 in each side wall 30 of the cross-head to receive a pin 31. The pins 31 may be placed in the positions in which they are shown through lateral, horizontally elongated openings 32 in the walls of the guides 23 and 23a. A support 33 is secured to the upper wall 34 of the central section 21 of the member 19 by means of screws 35. The support 33 extends substantially normal to the pis-

ton rods 11 and at the upper end thereof has bearings 36 for a crank shaft 37 provided with cranks 38 and 38a disposed respectively in the same vertical planes as the cross-heads 25 and 25a.

To slidably support a body 39, the support 33 has a slide 40 extending substantially normal to the plane defined by the piston rods 11. As best shown in Fig. 4, the slide 40 is of dovetailed cross-section and has converging side walls 41, one of which carries a gib 42. The body 39 comprises a casting 43 having a wedge portion 44 to slide vertically in the slide 40 and bearing supports or journals 45 and 46 secured to the outer face of the casting 43 by screws 47. The members 45 have inwardly faced recesses 48, and the member 46 has opposed recesses 48, carrying ball bearings 49 to receive trunnions 50 which project diametrically from blocks 51 of cylindrical form.

The blocks 51 have bores 52 to slidably receive rocker arms 53 and 53a, the lower ends of which are connected to the cross-heads 25 and 25a, and the upper ends of which are connected by means of connecting rods 54 and 54a with the cranks 38 and 38a. The body 39, the trunnions 50, and the blocks 51 cooperate in forming adjustable pivot means for the rocker arms 53 and 53a so that the angular swinging movement of the rocker arms resulting from the oscillation of their upper ends by the cranks 38 and 38a may be varied, thereby varying the distance the piston rods 11 and the pistons 12 are caused to move as the result of the movement of the lower ends of the rocker arms 53 and 53a. Vertical movement of the body 39 so as to carry the trunnions 50 and the blocks 51 upwardly or downwardly relative to the respective ends of the rocker arms 53 and 53a is provided in the form of a screw 55 which makes threaded engagement with the upper part 56 of the body 39, as shown in Fig. 2, and is restrained from vertical or axial movement by collars 57 and 58 lying on opposite sides of a bracket 59 provided with an opening 60 through which an upper portion of the screw 55 passes, the upper extremity 61 of the screw 55 being prepared for engagement by a tool to rotate the screw 55 and thereby adjust the pivot means of the rocker arms while the metering pump is in operation.

The upper ends of the rocker arms 53 and 53a are provided with threads 62 for the securement of clevises 63 carrying pivot pins 64 through which connection with the outer ends of the connecting rods 54 and 54a is made. As best shown in Fig. 3, the lower ends of the rocker arms 53 and 53a are flattened so as to provide tongues 66 to project into the vertical openings 28 of the cross-heads 25 and 25a, these tongues 66 having openings 67 to receive the central portions of the pivot pins 31, screws 68 being provided. The confinement of the cross-heads 25 and 25a in the guides 23 and 23a constrains these cross-heads and the pivot pins 31 to straight line movement parallel to the lines of movement of the piston rods 11. Accordingly, the rocker arms 53 and 53a slide up and down through the blocks 51 as they are rocked by the action of the cranks. The portions of the rocker arms respectively above and below the pivot means 50 constitute levers which may be varied in length. The distance through which the upper end of each rocker arm is swung remains constant, since the upper ends of these rocker arms are directly connected to the cranks by the connecting rods.

The movement of the cross-heads 25 and 25a, and of the pistons 12 connected thereto, may be made much shorter than the movement of the connecting rods, as when the block 39 is in or below a lowered position, such as shown in Fig. 2. As the body 39 is raised the swing of the lower ends of the rocker arms will be correspondingly increased; therefore, by use of the screw 55 it is possible to vary the distance of travel of the pistons 12 from one extreme to the other and to cause these pistons 12 to selectively continuously pump a flow of fluid of a volume within the limits of adjustment of the device. Ordinarily the crank shaft 37 is operated at constant speed and the rate of fluid discharge is controlled by adjustment of the position of the pivot means 50. The slide 40 is provided with calibrations 70 to indicate the displacement of the metering pump for different settings of the body 39 along the slide 40.

We claim as our invention:

1. In a metering attachment for use with a displacement pump of the character described having a reciprocative wall and a stationary wall 25 structure to cooperate with said reciprocative wall, the combination of: an extension connected to said stationary wall so as to project therefrom, and having a guide lying along a line agreeing with the direction of movement of said reciprocative wall, a body slidable in said guide; a rod connecting said body to said reciprocative wall; a support projecting at right angles to said line, said support having a slide along a side thereof and bearing means to the outer end thereof; a member supported by said slide, said member having pivot means; a rocker arm pivotally connected to said body and projecting outwardly therefrom along said slide; a block having an opening therein through which said rocker arm is slidably, said block being connected through said pivot means with said member; a crank carried by said bearing means; a connecting rod connecting the outer end of said rocker arm with said crank so that rotation of said 40 crank will produce reciprocation of the outer end of said rocker arm and a swinging movement of said rocker arm on said pivot means; and a screw 45 extending along said support to move said member on said slide whereby to move said pivot means.

2. In a metering drive device of the character described, for use with a displacement pump member having a movable wall and inlet and outlet valve means, the combination of: a rocker 55 arm having its inner end connected to said movable wall; a supporting member disposed intermediate the ends of said rocker arm; a body carried by said supporting member so as to be movable along said rocker arm; pivot means 60 carried by said body, said pivot means engaging said rocker arm and being movable therealong as said body is moved on said supporting member so that the distance of said pivot means from the respective ends of said rocker arm may be varied; means operative to impart an oscillating motion to the outer end of said rocker arm so that it will swing on said pivot means and impart movement through its inner end to said movable wall; means providing calibrations; and 65 a member moving relative to said calibrations in accordance with the movement of said pivot means along said rocker arm.

MARTIN MADSEN.
